(57) **CLAIM**

The ornamental design for a vehicle mounted storage tote, as shown and described.

DESCRIPTION

FIG. 1 is a perspective view of a vehicle mounted storage tote with the cover closed.

FIG. 2 is a view of the front side of a vehicle mounted storage tote.

FIG. 3 is a view of the back side of a vehicle mounted storage tote.

FIG. 4 is a view of the top of a vehicle mounted storage tote.

FIG. 5 is a view of the right side of a vehicle mounted storage tote; and,

FIG. 6 is a view of the left side of a vehicle mounted storage tote.

No view of the bottom of the tote is shown. The bottom is unornamented and not part of the claimed design.
